(57) **CLAIM**

The ornamental design for a vehicle board bag as shown and described.

DESCRIPTION

FIG. 1 is a top view of a vehicle board bag in accordance with aspects of the present subject matter, particularly illustrating the vehicle board bag when closed.

FIG. 2 is a first or right side view of the vehicle board bag illustrated in FIG. 1, particularly illustrating the vehicle board bag when closed.

FIG. 3 is a front view of the vehicle board bag illustrated in FIG. 1, particularly illustrating the vehicle board bag when closed.

FIG. 4 is a second or left side view of the vehicle board bag illustrated in FIG. 1, particularly illustrating the vehicle board bag when closed.

FIG. 5 is a rear view of the vehicle board bag illustrated in FIG. 1, particularly illustrating the vehicle board bag when closed.

FIG. 6 is a rear view of the vehicle board bag illustrated in FIG. 1, particularly illustrating the vehicle board bag when unstrapped.

FIG. 7 is another top view of a vehicle board bag in accordance with aspects of the present subject matter, particularly illustrating a vehicle board received within the vehicle board bag when the vehicle board bag is closed.

FIG. 8 is another first or right side view of the vehicle board bag illustrated in FIG. 1, particularly illustrating the vehicle board received within the vehicle board bag when the vehicle board bag is closed.

FIG. 9 is another front view of the vehicle board bag illustrated in FIG. 1, particularly illustrating the vehicle board received within the vehicle board bag when the vehicle board bag is closed.

FIG. 10 is another second or left side view of the vehicle board bag illustrated in FIG. 1, particularly illustrating the vehicle board received within the vehicle board bag when the vehicle board bag is closed.

FIG. 11 is another rear view of the vehicle board bag illustrated in FIG. 1, particularly illustrating the vehicle board received within the vehicle board bag when the vehicle board bag is closed.

(Continued)

FIG. 12 is another rear view of the vehicle board bag illustrated in FIG. 1, particularly illustrating the vehicle board received within the vehicle board bag when the vehicle board bag is unstrapped.

FIG. 13 is a perspective view of the vehicle board bag illustrated in FIG. 1, particularly illustrating the vehicle bag when closed; and,

FIG. 14 is a perspective view of the vehicle board bag illustrated in FIG. 1, particularly illustrating the vehicle bag when opened.

Contour lines and/or surface shading, to the extent applicable, are illustrated simply for purposes of highlighting the solid-rendering, and, thus, form no part of the claimed design. Additionally, the images of the vehicle board are shown simply for purposes of illustrating the environment, and, thus, form no part of the claimed design.
